UNITED STATES PATENT OFFICE.

ARLINGTON MOORE, OF NEW YORK, N. Y., ASSIGNOR TO MOORE INVENTIONS CORPORATION, OF WORCESTER, MASSACHUSETTS, A CORPORATION OF MASSACHUSETTS.

PROCESS OF AND APPARATUS FOR MAKING SANITARY METAL CANS.

Application filed April 15, 1922, Serial No. 553,213. Renewed December 21, 1926.

My invention relates to improvements in methods of sealing sanitary cans, such as used in shipping food products and the like. Heretofore it has been the practice to seal so-called sanitary tin cans by employing gaskets, or the equivalent, in the seams between the can body or wall and the portions forming the top and bottom of the can respectively. Such construction has not always been found effective to produce a satisfactory seal.

The present invention relates to forming the heading seams of sanitary cans in a highly improved manner, whereby they are made air and liquid tight without the necessity for gaskets, linings or the like.

Another feature relates to a method of applying high pressure to the heading seam by which the component metal parts are secured together in close and intimate contact, and a can of great strength is produced.

Other objects will appear from the following description taken in connection with the accompanying drawings in which Fig. 1 is a transverse vertical section of a portion of a machine for sealing cans sufficient to show its operation in accordance with the process of my invention. Fig. 2 is a horizontal section taken on the line 2—2 of Fig. 1. Fig. 3 is a section on the line 3—3 of Fig. 1, and viewed from below. Fig. 4 is a section on the broken line 4—4 of Fig. 3. Fig. 5 is a sectional view of the seam forming rolling device taken on line 5—5 of Fig. 2. Fig. 6 is a part sectional view of the can with the heading seam partly rolled, and the rolling device in place. Fig. 7 is a view similar to Fig. 6, but with the seam forming device in place for turning or rolling the heading seam over for a second time. Fig. 8 is a side view of a completed can with parts broken away, and Fig. 9 is an enlarged sectional view showing the formation of the can heading seam.

The present invention is concerned more especially with the formation of the heading seam for attaching the can head or heads to the can body. While the heading seam of the present invention may be used only on the lid end of the can, and the can bottom may be secured in place in any desired way, the top and bottom closures for the can are preferably formed in the same manner and in such case a description of the making of one will suffice for both.

The side wall or body of the can may be made in any desired manner, and in the present application a can body of conventional form is illustrated without particular reference to the precise mode of construction of the side seam of the can body, which may be made in various ways, two construction of can bodies adapted for use with the present invention being disclosed in my copending applications filed on even date herewith, Serial Numbers 553,211 and 553,212.

The side wall or can body portion 20 of the can is provided with a peripheral outwardly extending shoulder 21 near the end thereof, the extreme end portion 22 of the can body beyond the shoulder 21 being of somewhat larger diameter than the principal portion of the can body 20. In forming such shoulder 21 the end portion 22 of the can body is outwardly displaced or expanded with respect to the main portion of the can body a distance which is substantially equal to the thickness of the can body, as will be seen on reference to Figs. 6 to 9, though such displacement may be more or less than this precise amount. The provision of shoulder 21 makes it possible to support and hold the can firmly during the formation of the heading seam, and also serves as a stop for the lid or closure when put in place in the can body.

The closure member or head 23 which may form either the top or the bottom of the completed can or both, as already indicated, is provided with a marginal flange 24, which is turned or flanged over, so as to lie closely against the expanded portion 22 of the can body, when the closure member is inserted in place resting against the shoulder 21 in the can body.

The enlarged end portion 22 of the can body 20 is longer than flange 24 of lid 23, the relative dimensions thereof being preferably about as indicated in Fig. 6 of the drawings.

In forming the heading seam, outer end 25 of the expanded end portion 22 of the can body extending beyond the lid flange 24 is turned inwardly over the edge of said flange 24, through an angle of 180°, whereby the projecting portion 25 at the extreme edge of the can body is brought from the position shown at the right hand portion of Fig. 6 to that shown at the left hand portion of the same figure.

110

The next step consists in turning these folded over parts of the heading seam shown at the left hand portion of Fig. 6 a second time, bringing same from the position shown at the right hand portion of Fig. 7 (this is the same position as shown at the left hand portion of Fig. 6) to the position shown at the left hand portion of Fig. 7. The bend line for this turning operation preferably comes at substantially the middle of the lid flange 24, as will be apparent from Fig. 7 of the drawing. When this is done a seam is formed about the end of the can which, in the case of the can body being made of a single thickness of sheet metal, comprises five layers of metal, as shown in Figs. 7, 8 and 9, with the portion 25 originally forming the extreme outer edge of the can body in the center of the five-ply seam so made up.

This marginal seam is subjected to high pressure applied both to the sides and to the end of the seam, while the can body is firmly held by means of the shoulder 21, thus bringing the parts into the relative positions shown in Fig. 9 of the drawings. The pressure applied is preferably sufficiently great to cause an actual flowing or elongation of the metal, resulting in the filling out of all open spaces in the seam with the metal to produce substantially a thick, heavy ring about the can head, as shown at 26, Fig. 9. In this way the parts are forced into such intimate contact that a junction is secured equivalent in effect to the formation about the can head of a welded ring of substantial thickness and great mechanical strength. The metal parts of the ring seam 26 being in intimate contact throughout an extended surface comprising a number of reversed bends or folds, make a completely air tight seal, and gaskets, linings or the like heretofore required are completely dispensed with.

It will be seen that in the formation of the completed seam certain portions of the metal making up the seam are turned over through an arc of as much as 270° to a complete circle of 360° , part 25 of the can body, for example, being turned over in the finished position to the full extent last named to lie substantially parallel to and to extend in the same direction as in its original position shown at the right hand portion of Fig. 6 of the drawings.

In the drawings I have illustrated the essential parts of one form of apparatus for carrying out the process of the present invention. Such showing is illustrative only and for the purpose of showing apparatus by which the process may be carried out.

Means are provided in the illustrative apparatus for supplying the cans to the heading device to be described shortly. In the form shown, the can 27 when delivered to

the heading device is supported in the rotatable holder 28 and has the lid 23 inserted in place therein. Holder 26 may form part of an automatic conveyor, if desired, as is customarily used with can sealing machines. It will be understood that the closure seaming operation may be applied to put the bottom in an unheaded can body, or may be utilized to seam the lid in place in completing the operation of making a can or sealing a can after it has been filled, or for other purposes.

Means are provided for firmly and securely holding the can in place during the operation of making the heading seam. In the form shown, the can is received and held by a plurality of jaws 29, 29. Four such jaws are shown in the drawings, each extending through 90° of a circle, and the holding faces 30 of such jaws 29 have a shoulder 31 formed therein, adapted to support the can 27 by means of the shoulder 21 formed on the can body. The height of the holding portion 32 of the jaws 29 above the shoulders 31 preferably determines the depth of the heading seam 26 made in the completed can.

Resilient means are provided for normally holding the said jaws 29 in open position. In the construction shown, the jaws 29 are supported in the encircling ring 33 by means of bolts 34, which bolts 34 are pushed outwardly by the springs 35. The ring 33 is mounted to turn in its supporting head 36 in any desired way, and if desired, ball bearings 37 may be supplied for this purpose, the head 36 being preferably non-rotatable.

Guide means in addition to the bolts 34 are preferably provided for guiding the clamping jaws 29 in their movement in and out with respect to the ring 33. In the form shown, the jaws 29 are each provided with a central lug or tail-piece 38 which work in slots 39 formed in the under surface of ring 33.

Means are provided for moving the jaws 29 inwardly against the action of spring 35 to clamp the jaws about the end of the can to hold the same securely in place. In the form shown, the means utilized for this purpose serve also to impart rotation to the jaws 29 and the ring 33 which turns therewith. The device provided for this purpose, as shown, comprises the rotary and reciprocatory hollow cylinder 40, adapted to turn and slide in a bearing 41 provided therefor in the supporting head 36. The cylinder 40 is provided with a plurality of downwardly extending projections 42, wedge-shaped at their lower ends, as shown at 43 in Fig. 1, adapted to enter notches 44 formed in the jaws 29 and likewise having wedge-shaped or inclined surfaces 45 adapted to be engaged by the wedge-shaped surfaces 43 when the cylinder 40 is depressed, thus forcing the

jaws 29 inwardly to clamp and hold the can. The range of longitudinal movement of the cylinder 40 is limited, so that at no time are the downwardly extending fingers 52 completely withdrawn from the notches 44 in the jaws 29, and thus the cylinder 40, jaws 29 and ring 33 rotate together.

Rotation may be imparted to the reciprocable cylinder 40 in any desirable way, as, for example, by means of the pinion 46 in sliding engagement with the elongated annular gear teeth 47 formed on the inner wall of the hollow cylinder 40.

The means so far described serve to permit the insertion of a can, which after being inserted is held firmly and securely, and rotated while so held. While this arrangement is preferable, it being deemed desirable to rotate the can with respect to the relatively stationary seam turning and forming devices, and such construction is illustrated in the present drawings, it should be understood, however, that relative rotation between the can and the seam turning and forming devices may be secured in any desired way, as by having one thereof stationary and the other rotating, or having each rotating in opposite directions, or in other ways.

In forming the turned over seam a roller 48 is used. The longitudinal axis of the roller 48 is preferably arranged in a plane at right angles to the longitudinal axis of the can, and such roller 48 is so located and directed that the can rotates, the roller 48 comes in contact with the upstanding edge of the can body and later with the partially folded seam to turn the same inwardly. In the form shown, the longitudinal axis of the roller 48 is so located with respect to the periphery of the can as to form a chord of the circular periphery of the can, part of the roller toward one end extending outwardly beyond the periphery of the can and another part toward the other end extending inwardly beyond the periphery of the can, as shown clearly in the sectional view of Fig. 2. The arc of the chord formed by the axis of roller 48 is always under one-third of the can body circumference and is preferably located as indicated by section line 5-5, Fig. 2. A second roller 49 turning on a vertical axis, that is, an axis at right angles to the longitudinal axis of roller 48, or parallel with the axis of the can body, is mounted on the same arm 50 that carries the roller 48 and serves to complete the turning over of the seam parts, as will be apparent from the showing of Figs. 5, 6 and 7. Arm 50 is secured to shaft 50^a by which it is operated by any suitable control mechanism.

The turning of the portion 25 of the can body over from the position shown at the right hand portion of Fig. 6 to the position shown at the left hand portion thereof may

be accomplished either by a slow or by a relatively rapid depression of the arm 50 carrying the rollers 48 and 49, the arm 50 being held to bring the roller 49 outwardly against the seam as same is being formed. After the seam has been thus partially formed, the arm 50 is further depressed to make the second operation of turning the seam parts, as shown in Fig. 7, and in making this second operation on the seam it has been found desirable that the depression of arm 50 be relatively rapid or abrupt, so that the completed seam may be formed by turning over the seam parts at the desired bending line about the middle of the lid flange 24, as shown in Fig. 7.

After the seam parts have been turned into the position shown at the left hand portion of Fig. 7, high pressure is applied thereto both radially from the axis of the can to the exterior, and longitudinally of the can at the extreme end of the heading seam, forming the completed seam as shown at 26, Fig. 9.

The means provided for this purpose comprise the roller 51 having the part 52 adapted to bear inwardly against the inner side of the seam 26, and provided with the flange 53 adapted to apply similarly great pressure to form the end of the completed seam. The jaws 29 serve as a stop for the roller flange 53, so that the holding face 30 of the jaws 29 determines the height of seam 26 above the shoulder 21, as stated above. Such roller 51, comprising the parts 52 and 53, is mounted on the shaft 54, which is rotatably supported as by ball bearings 55 in the eccentric sleeve 56, which is adapted to be turned in its bearing 57, thus forcibly bringing the roller 51 into high pressure contact with the interior of the can seam and compressing same under great pressure as it is held by the clamping jaws 29. Application of pressure longitudinally upon the thrust bushing 57^a serves to apply similarly great pressure by means of the roller flange 53 to the outer edge or end of the can seam, and the combined effect of pressure applied in the manner described, which may be sufficient to even cause an actual flowing of the metal under pressure, results in the production of the finished seam 26 as shown in Fig. 9 of the drawings.

After the seam is completed, the eccentric sleeve 56 with its associate mechanism is withdrawn upwardly, as is also the arm 50 with its associated mechanism. The cylinder 40 being moved upwardly, releases the jaws 29 which are expanded outwardly by the springs 35, thus freeing the can, which is withdrawn and a new can substituted, and the operation as described may be repeated indefinitely.

I claim:

1. The process of securing lids to bodies

of sanitary metal cans, which comprises providing a can body having the end thereof outwardly expanded and providing a shoulder at the base of the expanded portion, supporting the can body against endwise movement by supporting means applied to said shoulder, inserting within the expanded portion of the can body a lid having a peripheral flange thereon, the lid resting against such shoulder and the outer edge of the flange being received within the expanded portion of the can body which extends there beyond, turning the extreme end portion of the can body inwardly over the lid flange and parallel thereto and into close contact therewith on the inner side, and turning over these parts a second time inwardly into parallel folds upon a fold line located at substantially the middle of the lid flange, and applying high radial and endwise pressure to the seam so formed while the can is supported by supporting means applied at said shoulder, whereby a heading seam is provided comprising five parallel folds of metal with the turned over extreme edge of the can body in the middle thereof and all the metal parts in close and intimate contact and union, thereby securing an effective seal and enabling gaskets, linings and the like to be dispensed with.

2. The process of securing heads to bodies of sanitary metal cans, which comprises providing a can body having an expanded end portion extending radially outward beyond the main part of the can body and a shoulder where said end portion joins the main part of the can body, supporting said can body by shouldered supporting means adapted to engage the shouldered portions of the can body, and seaming a lid to said can body while so supported.

3. The process of securing heads to bodies of metal cans, which comprises providing a can body with an outwardly extending shoulder near the end thereof and with a relatively expanded end portion beyond said shoulder, placing a flanged lid in the can body against said shoulder, seaming the end of the can body and lid flange together by inwardly turning movement, and applying high pressure to the seam in the axial direction of the can, while supporting the can against such pressure by supporting means applied to the shoulder formed on the can body and extending beyond the shoulder to provide an annular abutment against application of radial pressure.

4. Apparatus for seaming heads to bodies of sanitary cans, which comprises a roller extending across the edge of the can body, the roller axis forming a chord of the circle defined by the end of the can body, and means for rotating the can body with respect to the roller.

5. Apparatus for seaming heads to bodies

of sanitary cans, which comprises a turning member extending horizontally across the edge of the can body on an axis forming a chord of the circle defined by the end of the can body and adapted to turn the edge of the can body inwardly over the flange of an inserted lid, a second roller having an axis substantially parallel to the can body axis adapted to force the turned edge flat against the lid flange, and means for causing rotation of the can body relative to the rollers.

6. Apparatus for seaming heads to bodies of sanitary cans, which comprises a pair of rollers having their axes at right angles to one another, one arranged with its axis forming a chord of the circle defined by the end of the can body and adapted to turn the edge of a can body inwardly and the other to force the turned edge flat against the lid flange and means for causing rotation of the can body relative to the rollers.

7. Apparatus for seaming heads to bodies of sanitary cans, comprising a pair of rollers having their axes at right angles and adapted first to turn the edges of the can body inwardly over the flange of an inserted lid and flat against the can body and next to turn the turned over edge and lid flange inwardly upon a fold line located at about the middle of the lid flange, means for causing rotation of the can body with respect to said rollers, and means for moving said rollers longitudinally with respect to the axis of the can body.

8. Apparatus for sealing a sanitary metal can, comprising means for clutching the can body with a flanged line in place therein, a roller extending across the edge of the can body at an oblique angle and adapted to apply pressure to the edge portion of the can body for bending the edge over inwardly, means for aligning the fold with the wall of the can, and means for applying pressure to the folded metal to form an intimate union of the metal parts.

9. Apparatus for sealing a sanitary metal can, comprising means for clutching the body of a can near the end to be sealed with a flanged lid in place therein, a roller positioned at an oblique angle relative to the edge of the can and adapted to bend said edge over, a second roller aligned with the edge of the can and adapted to fold the edge into alignment with the wall of the can, means for moving said rollers axially of the can to produce a second inward folding of the seam parts, and means for applying pressure to the folded metal to form an intimate union of the metal parts.

10. Apparatus for sealing heads to bodies of sanitary metal cans, comprising a supporting arm with a pair of rollers thereon having their axes at right angles to one

another, one adapted to extend horizontally across the end of the can at an oblique angle, and the other a following roller adapted to force an edge turned over by the first roller into alignment with the can body wall.

11. The process of forming a heading seam for sanitary metal cans, which comprises providing a can body with its end shouldered outwardly, supporting said can body by the shoulder in an annular exterior support having a corresponding shoulder formed thereon and extending therebeyond, the edge of the can body extending beyond 10 the support, inserting a flanged lid to rest on said shoulder within the can body, turning over the can body edge and lid flange

into a multiple fold seam and applying radial pressure against the turned over seam parts within and against the support to 20 flatten out the seam and to pack the folded parts together.

12. Apparatus for seaming heads to bodies of sanitary cans, which comprises a turning member extending across the edge of the 25 can body, the axis of the turning member forming a chord of the circle defined by the end of the can body, the arc of which chord is under one-third of the body circumference, and means for rotating the can body with 30 respect to the turning member.

In testimony whereof, I have signed my name hereto.

ARLINGTON MOORE.
